CLAIM

The ornamental design for an insole, as shown and described.

DESCRIPTION

FIG. 1 is a top perspective view of an insole for use on the left foot, showing our new design;

FIG. 2 is a top view of the insole of FIG. 1;

FIG. 3 is a bottom view of the insole of FIG. 1;

FIG. 4 is a first side view of the insole of FIG. 1;

FIG. 5 is a second side view of the insole of FIG. 1;

FIG. 6 is a front view of the insole of FIG. 1;

FIG. 7 is a back view of the insole of FIG. 1;

FIG. 8 is an enlarged top perspective view of FIG. 1; and, FIG. 9 is an enlarged top perspective view of FIG. 1, wherein the connector is shown in inclined condition.

The right side insole is a mirror image of FIGS. 1-9.

The broken line portions of FIGS. 1-9 are included to show environmental use only and form no part of the claimed design.
